VEHICLE DOOR CONSTRUCTION

Fred J. Westrope, Detroit, Mich., assignor to The
Murray Corporation of America, a corporation
of Delaware

Application January 2, 1934, Serial No. 704,813

4 Claims. (Cl. 296—44)

My invention relates to vehicle bodies and particularly to the door structure therefor and the method of mounting the doors on the body.

Heretofore it has always been the practice to employ pivotal hinges, that is to say hinges having wing portions pivoted together which extend outwardly from the body. Such hinges not only produce an unsightly appearance but also offer a certain degree of resistance to the air which is objectionable on the present day type of streamline body. Some effort has been made to eliminate the unsightly appearance of the hinge by constructing a concealed hinge of the wing type made up from a plurality of links which, while an improvement over the present construction, is not entirely satisfactory in view of the weight of the door and the ruggedness that must be built in such hinges.

In practicing my invention, I materially advance the art of supporting doors on vehicle bodies by utilizing a pin and socket connection at the bottom, top or intermediate side edge of the door, in aligned relation and disposed within the thickness of the door to be invisible from the inside and outside of the body. In some instances the hinge may be employed only at the bottom to take the support of the door so that only a single hinge near the belt line or top of the body need be employed which may or may not project outwardly from the side of the vehicle. As a further extension of the invention, I may employ a concealed type of hinge in the place of the standard type at the belt line or top above referred to, made up of a plurality of links. This hinge will only be employed to position the door and not to support its weight which is entirely supported by the pivot and socket connection at the bottom edge of the door.

As a further extension of the invention a recess portion of the body adjacent to the door may be provided in which a hinge may extend along the side surface of the body to have the pivot thereof aligned with the pin and socket supporting the bottom portion of the door. Such a hinge will be visible from the side of the body but will be removed from the flow of air along the body side. However, as a preferred form, I employ both the pin and socket connections at the top and bottom edges of the door so as to have the pivotal support for the door entirely invisible from the exterior of the body. In this construction when the door is formed to have a portion extend over the wheel housing, I may align the pivots in offset relation from the door edges to have a portion of the door move inwardly

while another portion of the door moves outwardly.

When, however, the doors are both pivoted at the central portion I may eliminate the pillars and mount both edges of the door on the pin and socket pivots. In this construction, either door or both will be swingable without interfering with the other and at the same time the pillars are eliminated at the junction of the two doors. As a still further extension of my invention, I may employ a single door swung on pivots intermediate the forward and rear compartments so as to have the rear portion move in while the front portion moves out to have the front and rear compartments open to the egress or ingress of the occupants. In any of these constructions the pin and socket connection materially adds to the strength of the support for the door, enhances the appearance of the vehicle and provides a smooth side to the stream of air flowing thereacross.

Accordingly, the main objects of my invention are: to provide a pin and socket pivot support for a door which is mounted within the door structure so as to be invisible from the interior or exterior of the vehicle; to obtain proper spacing for the hinges of a door by mounting them intermediate the front and rear edges to have a portion of the door move inwardly while another portion moves outwardly; to provide a pin and socket pivot in the body portion of the door and a single small hinge near the belt line or top of the body to position the door, the weight of which is supported by the pin and socket pivot; to provide two doors pivoted in adjacent relation so as to eliminate the central pillar thereof by having the doors mounted at the top and bottom edges on pin and socket pivots to permit either one to swing relative to the other and to be sealed relative to each other when the doors are in closed position; to provide a single door for closing the front and rear compartments of a body pivoted intermediate its ends at the top and bottom of the door to have one portion swing inwardly while another portion swings outwardly and, in general, to materially strengthen the pivotal support for the door of a body in such manner as to enhance the appearance of the vehicle, to provide a more durable construction and to eliminate resistance to wind along the side of the vehicle.

Other objects and features of novelty of my invention will be either specifically pointed out or will become apparent when referring, for a better understanding of my invention, to the fol-

lowing description taken in conjunction with the accompanying drawings, wherein:

Figure 1 is a plan view of a vehicle body embodying features of my invention.

5 Fig. 2 is an enlarged sectional view of the structure illustrated in Fig. 1, taken on the line 2-2 thereof.

10 Fig. 3 is an enlarged sectional view of the structure illustrated in Fig. 1, taken on the line 3-3 thereof.

Fig. 4 is an enlarged sectional view of the structure illustrated in Fig. 1, taken on the line 4-4 thereof.

15 Fig. 5 is an enlarged sectional view of the structure illustrated in Fig. 1, taken on the line 5-5 thereof.

20 Fig. 6 is an enlarged sectional view of the structure illustrated in Fig. 1, taken on the line 6-6 thereof.

25 Fig. 7 is a view of a body, similar to that illustrated in Fig. 1, showing a modified form of my invention.

Fig. 8 is an enlarged sectional view of the structure illustrated in Fig. 7, taken on the line 8-8 thereof.

30 Fig. 9 is a view of a body, similar to that illustrated in Fig. 1, showing a modified form thereof.

Fig. 10 is a view of a body, similar to that illustrated in Fig. 9, showing a modified form thereof.

35 Fig. 11 is an enlarged sectional view of the structure illustrated in Fig. 10, taken on the line 11-11 thereof.

Fig. 12 is a view of a body, similar to that illustrated in Fig. 1, showing a modified form thereof,

40 Fig. 13 is an enlarged sectional view of the structure illustrated in Fig. 12, taken on the line 13-13 thereof.

The vehicle body illustrated in Fig. 1, comprises a body portion 15, a front door 16 and a rear door 17. The front door is constructed to have a pivot 18 and a hinge 19 mounted on a central pillar 21 of the body. The lower pivot 18 is illustrated enlarged in Fig. 3 as comprising a pin 22 and a socket 23 which substantially support the entire weight of the door, the pivot formed thereby being aligned with a pivot 24 on the hinge 19. This hinge is of conventional form except that it is much smaller than a standard hinge and only one hinge is employed in view of the pin and socket connection at the bottom of the door which substantially supports the door. In the construction herein shown the door is flanged outwardly at 25 to extend over the projecting floor portion 26 supported on the bracket 27.

45 The pin 22 is provided with a bracket 28 which is secured to the side sill portion of the body having an apertured extension 29 in which the pin 22 is screwed. The pin is provided with a passage 31 for the purpose of lubrication. Suitable means (not shown) retains the socket 23 supported on the paneling of the body in a rigid manner. In this construction the weight of the door is substantially supported at the bottom by the concealed pin and socket connection and a material reduction in strength is permissible in the hinge 19 which positions the door, rather than adds materially to its support.

50 In Fig. 1, I have illustrated a further extension of the invention wherein a pin and socket hinge 30 similar to the pivot 18 described in relation to the front door 16 is mounted inwardly of the edge of the rear door 17. Directly aligned with the pivot formed thereby is a hinge 32 of the concealed type. The hinge 32 is made up of a plu-

5 rality of links and, since material strength is not required at this portion of the door, the concealed type of hinge can successfully be employed at this point. The rear portion of the door rearwardly of the aligned pivots 30 and 32 moves inwardly as the front portion of the door moves outwardly in a manner which will be described more fully hereinafter.

10 The junction of the door at the pillar 21 is illustrated enlarged in Fig. 4, wherein the hinge 18 is illustrated as being entirely concealed from view and so located as to permit the door to freely pass by the edge of the pillar when the outer edge of the door is swung open. In Fig. 5, I have illustrated a section through the rear pivot 30 where-in a pin 33 is supported by the bracket 34 which is secured to the lower and side portion of the vehicle door by screws 35. The pin 33 rests within a socket 36 which is secured to the reinforcing elements 37 above the wheel housing, by screws 38. As pointed out hereinabove, in view of the offset relation of the pivot inwardly of the side edges of the door a portion of the door moves inwardly as illustrated in Fig. 6. The jamb face of the body 39 in which the door abuts is curved 25 on an arc struck from the center of the pivot 30 to permit all parts of the door to pass thereby. A suitable sealing element 41 is provided on the door for engaging the arcuate surface at the edge of the door opening of the body to completely 30 seal the door against ingress of moisture and which is further sealed in a conventional manner by the inner bead 42.

15 In Fig. 7, I have shown a further extension of the invention illustrated in Fig. 1, wherein the hinge 32 thereof has a hinge 42 substituted therefor which is recessed in the side of the body to provide a streamline effect thereto. As illustrated more clearly in the enlarged view of Fig. 8, a recess 43 is provided in the body in which an inner wing 44 is secured while a movable wing 45 is likewise disposed in the recess 43 and is flanged inwardly at 46 and secured to the door in a conventional manner. The pivot 47 of the hinge is aligned with the pivot of the hinge 30 and, while the hinge 42 is visible, it does not protrude from the side of the body and thereby provides a streamline effect thereto. In Fig. 7, I have illustrated a hinge 32 employed at the belt line or top of the door 16 similar to the hinge 32 employed on door 17 illustrated in Fig. 1. The hinge is invisible and is aligned with the socket hinge 18 employed at the bottom of the door which takes substantially all the weight of the door. The entire surface of the door is devoid of visible 55 hinges and a complete streamlining effect is provided.

20 As a further extension of my invention, I have illustrated in Fig. 9, a hinge arrangement for the door wherein hinges 18 and 38 are provided on the doors 16 and 17 respectively at the front and rear portions of the door. In a like manner, the upper portion of the doors have the same type of hinges 18 and 38 at the top side edges of the door aligned with the pivots of the hinges 18 and 38 at the bottom to form a more rigid hinge construction because of the ruggedness of the pin and socket arrangement. The rear door 17 has the pivot 38 aligned so that the rear portion 48 of the door moves inwardly while the front portion 49 moves outwardly, in a manner as specified hereinabove. In like manner, pivots 18 are aligned intermediate the edges of the front door so that the front portion 51 of the door moves inwardly while the portion 52, rearwardly of the pivot line, 75

moves outwardly. A complete seal is provided about the door in the manner above specified and illustrated more particularly in Fig. 6 for the portions moving in while the conventional sealing for the portions moving outwardly is employed.

In Fig. 10, I have illustrated the pairs of hinges 18 and 30 of the pin and socket type for securing the doors 16 and 17 to the body at their adjacent ends. The pillar 21 is entirely eliminated since the doors are supported on the top rail and bottom sill of the body. The edges of the door can be disposed closely adjacent to each other, as illustrated more particularly in Fig. 11. The adjacent rails of the door have a curved surface 53 to permit the edges 49 and 52 to readily pass by the opposite doors when either one is opened. In the same manner, both doors may be opened at the same time without conflicting with each other. A sealing strip 54 is carried by each of the doors which mate with each other to form a seal for the space between the doors. A conventional bead 42 is provided on one of the doors to seal the crack therebetween on the inside of the vehicle.

As a further extension of my invention, I have illustrated in Fig. 12 a vehicle body having a front and a rear compartment wherein a single door 55 is pivoted on supports 18 made up of a pin and socket connection and secured to the top rail and bottom sill immediately behind the front seat 56. The door will swing on the pivots 18 to have the rear portion 57 moved inwardly while the front portion 58 moves outwardly, as more clearly illustrated in Fig. 13. In view of the change in design of the body, this construction is becoming more practical and has certain advantages in that the control of the opening of the rear doors is wholly retained by the occupant of the vehicle or at least those occupying the front seat.

While I have illustrated two types of pin and socket hinges 18 and 30, it is to be understood that either or both may be employed on either type of door or in combination on a single door. It is to be also understood that other types of pin and socket elements may be utilized depending upon the shape of the door and body. The supporting of the door on the sill and top rail adds material strength to the pivot elements for the door and at the same time relieves the door jambs and pillars from the stress which they were subject to heretofore. The particular disposition of the pin and socket connection within the thickness of the door completely hides the pivotal elements from sight and streamlines the body. The application of

this type of hinge interjacent the front and rear edges of the door tends to more evenly balance the weight of the door and permits a portion of the door to move inwardly while other portions of the door move outwardly. The sealing of the door edges is reversed at the inwardly moving portion while the standard method of sealing is retained on the portions moving outwardly. When the pin and socket hinges are employed at the abutted edges of the door the pillar is entirely eliminated and the edges are closely disposed to each other and effectively sealed and so arranged that either or both doors may be opened independently of the other or at the same time without interference.

While I have described and illustrated several embodiments of my invention, it will be apparent to those skilled in the art that various changes, omissions, additions and substitutions may be made therein without departing from the spirit and scope of my invention, as set forth in the accompanying claims.

I claim as my invention:

1. A door for a vehicle body having top and bottom edges disposed substantially horizontal, and one edge substantially inclined to the vertical, a hinge element on one of said horizontal edges, and a second hinge element aligned with said first hinge element and disposed interjacent said top and bottom edges on said inclined edge.

2. A door for a vehicle body having a sloping side edge, a pin and socket connection at the bottom of the door inwardly of said edge, a concealed hinge in the sloping side edge of the door having a pintle aligned with said pin, whereby the pivotal support for the door is entirely invisible and the portion on either side of the aligned hinged pin and pintle is moved in opposite directions when the door is opened.

3. A door for a vehicle body having a sloping edge, pin and socket pivots disposed at the bottom of the door and the side edge, said pivots being in aligned relation, the portions of the door on either side of said alignment being movable in the opposite direction.

4. A door for a vehicle body having a sloping edge, pin and socket pivots disposed at the bottom of the door and at a side edge, said pivots being in aligned relation, the portions of the door on either side of said alignment being movable in the opposite direction, and sealing means for both portions of the door.

FRED J. WESTROPE.
